UNITED STATES PATENT OFFICE.

BRUNO V. E. NORDBERG, OF MILWAUKEE, WISCONSIN.

INTERNAL-COMBUSTION ENGINE.

Application filed December 8, 1917. Serial No. 206,236.

To all whom it may concern:

Be it known that I, BRUNO V. E. NORDBERG, a citizen of the United States, residing at Milwaukee, in the county of Milwaukee and State of Wisconsin, have invented a certain new and useful Improvement in Internal-Combustion Engines, of which the following is a specification.

This invention pertains to an improved fuel-heating chamber designed more especially for use in connection with internal combustion engines wherein the fuel is ignited by being intermixed with highly heated compressed air in the combustion chamber of the engine, as contradistinguished from that type of engine wherein the gas usually produced from a readily gasifiable fuel is intermixed with air, compressed and then exploded.

The heating chamber is designed more especially for use in heating the charges of oil in the presence of compressed air and thereafter causing the ejection of the charge in an atomized condition, such ejection being effected by the explosion within the chamber of the more highly volatile portions of the fuel charge. Experience with engines operated in the manner just noted has shown, particularly with crude oils, that it is necessary to regulate the temperature of the fuel-heating chamber so that it does not become too high,—this for the reason that if the temperature, particularly at the lower end of the chamber, becomes too high pressure is created inside said chamber, which prevents sufficient air from entering the same before the primary explosion takes place, with the consequence that the charge is not effectively ejected, and the unexploded portion of the fuel oil is not sufficiently atomized.

The main object of the present invention is to produce a chamber which will bring about the desired results, and to so water-jacket the chamber, and particularly the lower part thereof, that the burning in the chamber is commenced later and at a slower rate than would otherwise taken place, whereby the primary explosion will not occur until sufficient air has been forced into the chamber to effect the proper explosion and ejection of the fuel charge therefrom in an atomized condition.

A heating chamber which will effectually atomize the charge and eject the same by reason of a primary explosion within the

chamber is shown in the annexed drawings, wherein:

Figure 1 is a vertical transverse section, taken on the line 1—1 of Fig. 2;

Fig. 2 a similar view taken on the line 2—2 of Fig. 1, or at right angles to that shown in Fig. 1;

Fig. 3 a transverse horizontal sectional view, taken on the line 3—3 of Fig. 1;

Fig. 4 a similar view taken on the line 4—4 of Fig. 2; and

Fig. 5 an enlarged sectional view, showing certain details of construction.

Referring to the drawings, 1 denotes the cylinder head and 2 the heating chamber proper, cup-shaped in form and the interior of which is substantially cylindrical, see Fig. 2. The exterior lower portion of the wall of the heating chamber 2 is reduced somewhat in diameter and extends into the cylinder through an opening 3 formed in the cylinder head. Said chamber is likewise provided with an undercut groove or rim 4, in which is seated a copper ring 5, said ring bearing upon an inwardly-projecting portion of the cylinder head. A disk-like member 6 forms a closure for the upper end of the chamber, and a copper packing ring 7 is interposed between said disk and the adjacent inclined face 8 formed upon the inner wall of the chamber 2, said disk being provided with a central opening 9, the lower portion whereof (denoted by 10) inclines outwardly or is conically counter-bored. This counter-bore in the cover is provided for the purpose of allowing the spray from the fuel nozzle (not shown) to spread into the interior of the fuel heating chamber, without in any wise being obstructed. Overlying the disk-shaped member or cover 6 is a nozzle block 11, provided with an opening 12, in which the fuel nozzle of any approved type may be mounted. Said nozzle-block is held in place upon the cylinder, or cylinder-head, by bolts 13 (Fig. 2) and the heating chamber is secured to the lower end of said block by bolts 14. These latter bolts, as will be seen upon reference to Fig. 2, when tightened up, force the cover 6 firmly to place, causing the packing ring 7 to effect a tight joint between the cover and the heating chamber proper. As stated, bolts 14 secure the nozzle-block 11 and the heating chamber together, so that they and the conduit members hereinafter referred to may be withdrawn as one from

the cylinder head. Bolts 13, as they are turned inwardly, cause the ring 5 to effect a tight joint between the heating chamber and the inwardly-projecting underlying portion of the cylinder or cylinder-head, as the case may be.

5 Around the lower portion of the chamber 2 is formed an exterior annular groove 15, and a series of countersunk openings 16 extend from the bottom of said groove through the wall of the chamber 2 and into the lower portion of the chamber, as best shown in Figs. 2 and 4.

10 The nozzle block 11 is provided with oppositely-disposed recesses 17 in its side faces and likewise with lateral openings 18 in the upper portion thereof. The recesses 17 are designed to receive pipes or conduit members 19, into which are screwed pipes 20 15 extending through the lateral openings 18. The conduit members 19 are each provided with a lug 21, adapted to abut against the lower end of a screw 22 mounted in the nozzle-block 11, and to force said conduit member 25 downwardly into contact with a packing ring 23, surrounding the lower reduced end of the conduit member. Said packing ring bears against the upper face of the chamber 2 and the reduced portion enters 30 a recess or bore formed in the upper edge of the wall of the chamber, which bore is in line with an opening or conduit 24 which extends downwardly through the wall of the chamber to the lower end thereof. These 35 parts are duplicated, as will be seen upon reference to Fig. 1, upon each side of the head, and the conduits 24 open into a chamber 25 formed at the lower end of the heating chamber. This chamber is produced 40 by welding a disk-like element 26 to the lower face or bottom of the chamber, said face being preferably provided with a central lug 27. The member 26 may be welded by any suitable process, to the bottom of 45 the heating chamber, as for instance electrically, by acetylene torch, or otherwise. There is thus formed a water-way or channel comprising pipe 20, at the left, pipe or conduit 19, conduit 24, chamber 25, and 50 through similar conduits and pipes which are duplicated on the right, as shown in Fig. 1. This arrangement will carry the cooling water directly to the lower end or face of the heating chamber.

55 Experience has shown that, particularly with crude oils, it is necessary to regulate the temperature of the fuel heating chamber so that it does not become too high. In the use of heating chambers of this type the oil 60 is injected into the fuel-heating chamber through the fuel nozzle ordinarily in a fine spray early in the compression stroke of the engine. The air compressed by the engine piston gradually enters the fuel heating chamber through the openings 16 which ex-

tend inwardly from the annular groove or channel 15. If the temperature of the chamber, particularly at the lower end, becomes too high, a pressure is exerted inside of the chamber which prevents sufficient air 70 from entering the same before a primary explosion takes place within said chamber to effectively eject and atomize that portion or part of the fuel which does not partake of any action in such primary explosion. If, on 75 the other hand, the bottom of the chamber is jacketed by water in the manner above set forth, then the burning in the chamber is commenced later and is effected at a slower rate, and the primary explosion does 80 not take place until sufficient air has been forced into the chamber to effectively vaporize those particles of the charge which are readily volatilized.

85 Experience and trials have shown that it is material, however, to cool the bottom of the heating chamber, while on the other hand cooling of the upper portion of the chamber does not produce the desired effect.

90 The object of the annular groove 15 and the counter-bored openings 16 extending therefrom into the heating chamber is to more uniformly distribute the fire and the fuel issuing from the holes than would 95 otherwise obtain. In other words, this arrangement is to cause proper distribution of the fuel around the circumference of the cylinder-head and to shield the piston from the direct impact of the flame issuing 100 through the openings 16. Experience has demonstrated that where the holes extend directly to the outer surface or wall of the chamber the piston heats up considerably, particularly on higher loads, while with the groove and the counterbored holes arranged in the manner above specified the flame and fuel ejected from the chamber are deflected from the piston primarily by the lower wall of the groove or channel.

105 Having thus described my invention, what I claim is:

1. In combination with a cylinder of an internal combustion engine; a combined heating and fuel ejecting chamber projecting into the cylinder and into which the fuel is introduced and intermixed with air and caused to be expelled by the explosive action in part of said mixture, said chamber being provided with lateral openings for the discharge of fuel; and means carried by the chamber and extending to a point below the openings for cooling the chamber, whereby undue heating and consequent premature explosion of the mixture within the chamber is prevented.

115 2. In an engine of the internal combustion type, the combination of an engine cylinder; a combined fuel heating and ejecting chamber extending into the cylinder; and

a water jacket for the inner exposed end of said chamber, said chamber having an exterior annular groove extending about the same at a point above the water jacket, and 5 a series of openings extending from the bottom of the groove and opening into the interior of the chamber.

3. In an engine of the internal-combustion type, the combination of a cylinder head 10 having a shouldered opening formed therein; a heating chamber for the fuel, said chamber comprising a substantially cylindrical body provided with discharge openings adjacent its inner end, and a cover for 15 the upper end; a nozzle-supporting member overlying the cover; means securing said member to the cylindrical body and acting to force the cover to place; a packing interposed between the heating chamber and the 20 shoulder in the opening in the cylinder head; and means securing the nozzle-supporting member to the cylinder head and serving to force the heating chamber against

the packing and the underlying shoulder.

4. A fuel heating and charge forming 25 chamber for engines of the internal-combustion type, comprising in combination a cup-shaped member, having a water chamber formed in the lower portion thereof, with conduits extending upwardly therefrom in 30 the side walls of the member; a cover for the cup-shaped member, said cover having an opening extending therethrough; a casting bearing upon the cover, said casting having a nozzle opening therein in line with the 35 opening in the cover; means for securing the casting and cup-shaped member together; a pipe located in line with each of the conduits aforesaid, and communicating therewith; and means carried by the nozzle 40 casting for forcing and holding said pipes in place.

In testimony whereof I have signed my name to this specification.

BRUNO V. E. NORDBERG.
